UNITED STATES PATENT OFFICE.

JOHN KIRBY, JR., OF DAYTON, OHIO.

AUTOGRAPHIC REGISTER.

SPECIFICATION forming part of Letters Patent No. 469,666, dated February 23, 1892.

Application filed October 14, 1889. Serial No. 326,959. (No model.)

To all whom it may concern:

Be it known that I, JOHN KIRBY, Jr., of Dayton, county of Montgomery, and State of Ohio, have invented certain new and useful 5 Improvements in Autographic Registers, of which the following is a full, clear, and exact description, reference being had to the accompanying drawings, and to the letters and figures of reference marked thereon.

10 My invention relates to an autographic register in which a plurality of strips of paper are unwound from one or more delivery-reels and pass over a writing-tablet carrying carbon-paper or other suitable manifolding material, which is interposed between the paper strips, whereby a number of impressions may be made by one writing, the strips being separated after leaving the manifolding material, the lower strip passing to a place of concealment within the register-case and the other strip or strips passing outside of the case, where the portion written upon may be severed from the remainder of the strip or strips.

15 The objects of my invention are to provide means for severing and filing within the register-case slips severed from one of the several paper strips on which copies of writing are made, to provide means for making a printed impression upon one of the strips at each operation of the register, and to provide means for feeding the paper through the machine in such manner that only the required length of strips is moved forward at each operation. I accomplish these objects by the 20 mechanism shown in the accompanying drawings, wherein—

Figure 1 is a broken perspective view of my register with the several working parts in the positions they occupy when the paper has been 25 moved forward, the under strip severed, the movable blade of the paper-cutter at the point of release, and the filing-arm about to be brought into operation, one of the hinged ends of the case being shown in dotted lines partly open. Fig. 2 is a longitudinal central sectional view of the register, looking to the right, the cutter-operating cam being shown by dotted lines in the position it occupies when the requisite quantity of paper has been moved 30 forward and the cutter is about to be brought into operation by the reverse movement of the crank. Fig. 3 is a longitudinal central

sectional view of the register, looking to the left, with the filing-arm at the point of release after having performed its function. Fig. 4 55 is a plan view of the register with a portion of the top of the case removed. Fig. 5 is a transverse vertical sectional view of the register, taken on the line $\alpha\alpha$ of Fig. 4. Fig. 6 is a perspective view of an ordinary self-inking hand-stamp adapted for use in my register. Fig. 7 is a detail view clearly showing the spring interposed between the end of the movable blade of the cutter and the sliding arm. Fig. 8 is a perspective view of a tag 60 and fastener for binding the severed slips when taken from the register-case. Fig. 9 is a perspective view illustrating the manner of transferring the slips from the file to the binder shown in Fig. 8. Fig. 10 is a perspective view 65 of a bunch of slips bound ready for filing away for future reference.

Referring to the drawings, A represents the register-case, preferably of metal, consisting of the two sides 1 2, front 3, hinged to a 70 fixed portion 4, hinged back 5, fixed top portion 6, in which there is a sight-opening or window 7, a removable top portion 8, having an opening 9, through which the writing is done, and cross-bars 10 for connecting the 75 sides of the case, the whole being hinged and locked to a base B.

C is the main shaft journaled in the sides of the case and provided at one end outside of the case with a crank D and on its opposite end inside the case with a cam e. On this shaft is loosely mounted a feed-roller or paper-propelling cylinder E, to one end of which is rigidly secured a ratchet-disk F, having one series of teeth 11 on its periphery 90 and another series 12 on its side, and on the shaft near this disk is rigidly secured a wheel G, which I term the "pawl-carrier," provided on its inner side with a pawl 13, which engages with the teeth 12 on the disk and on its outer 95 side with two lateral pins 14 and 15, the shaft C, crank D, and pawl-carrier G constituting what I term the "feed-roller-operating mechanism." The cylinder is provided on its periphery near each end with a series of pins 16, 100 for a purpose hereinafter explained.

H represents what may be termed a "sliding" or "movable" arm or frame, comprising a horizontal base-bar h , a vertical bracket h'

and a horizontal arm h^2 , projecting forward of the bracket, the whole being preferably formed integral. This frame is movably secured to the side 1 of the case by means of 5 screws 17, passed through a slot 18 in the base-bar and also through a slot 19 in the arm. It is given a forward sliding movement by means of the cam c, secured on the end of shaft C, coming into contact with the rear edge 10 of an arm a, on which there is a lateral pin 20, (seen dotted,) which contacts with the bracket h' of frame H, the lower end of the said arm being pivoted to the base-bar and provided with a toe 21, on which bears a 15 spring 22, secured to the base-bar, the purpose of this spring being to hold the arm up in position to be operated on by the cam. A coil-spring 23, one end of which is secured to the case and the other to the frame, serves to 20 return the frame to its normal position.

I represents guides for the slip of paper to be filed, formed by laterally-extending flanges 24, secured to the sides 1 and 2 of the case, the guides being curved so as to direct the 25 slip to a position over the file f, located in the forward part of the register-case, which part forms the filing-compartment, the file being a small tube removably secured in the base of the register and provided with an enlarged removable spear-shaped head 25, the latter having a shank fitting snugly in the tube, as seen in Fig. 3.

To lugs 26 and 27, projecting inwardly from the sides of the case near the top and adjacent to the guides I, is secured the stationary 35 blade J of a paper-cutter for severing the slip of paper to be filed. The movable blade J' has a curved tongue j at one end, which is pivoted to the lug 26 underneath the corresponding end of the stationary blade. The 40 opposite end of the movable blade is slotted at 28, and is connected with an inwardly-projecting lug 29 on the arm h^2 of frame H by a screw 30, passing through the slot and taking 45 into the lug, the slotted connection permitting this end of the blade to move in the arc of a circle, so as to make a shearing cut. Between the lug 29 and the end of blade J' there is a spiral-spring s, whose function is to 50 keep the movable blade in close contact with the under side of the stationary blade while making a cut.

For the purpose of holding the paper while the slip is being severed from the strip I employ two pressure-arms K, each of which 55 co-acts with one of the guides I, these arms being carried by a rock-shaft 31, journaled in the sides of the case. The arms are depressed by a shoulder on the sliding arm h^2 of frame H riding over a finger 32 and thereby rocking the shaft forward, a coil-spring 33, attached to the case and to another finger 34 on the shaft, serving to return the pressure-arms to their 60 normal position.

65 L is a filing-arm formed of wire with a loop l at its free end to pass over the file, its other end being connected with a rock-shaft 35,

which is journaled in the sides of the case. On one end of this shaft is fixed a lever M, having a counter-weight m. This lever, which 70 is operated by the pin 14 on the pawl-carrier G, is in two sections, the upper one, which is curved at its upper end, being hinged at 36 to the lower one in such a manner that it will turn on the hinge only in the rearward direction. A leaf-spring 37, attached to the lower section of the lever and bearing against the upper section, serves to return the latter to its proper position.

N is a printing device of the ordinary self-inking hand-stamp variety, located slightly above the fixed portion 6 of the top of the case. Through its handle is passed a rod 38, to each end of which is secured a vertical arm 39, and to the lower end of each arm is pivoted a link 40, one of which has a downwardly-hanging extension 41, with which, in the forward movement of sliding frame H, the end of arm h^2 comes into contact and causes the printing device to make an impression, the other ends of the links 40 being pivoted on a rod 42, journaled in the sides of the case. A leaf-spring 43, secured to the case, bears against the extension 41 and serves 90 in an obvious manner to return the printing device to its normal position after each operation.

For purpose of illustration I have shown a single reel O journaled in the rear portion of the case, and on which are wound in the 100 present instance three paper strips 44 45 46, one over another, as seen in the drawings. These strips, which are perforated along their sides, pass over small rollers 47 48 49, thence over a writing-tablet P, on which there are 105 sheets of carbon-paper or other suitable manifolding material 50, which is interposed between the strips, and thence onto cylinder E, whose pins 16 engage with the perforations in the paper strips, the paper being pressed on 110 the cylinder to insure such engagement by means of two pressure-rollers 51, and thence on leaving the cylinder the upper two strips are passed out of an opening 52 in the top of the case, while the lower strip is passed under 115 the sight-opening 7 in the fixed portion 6 of the case, the latter strip in the operation of the machine being borne to the guides on strippers 53, which also serve to raise the paper strips clear of the pins 16 on cylinder 120 E. These strippers consist of four wires, secured at one end to a cross-bar 10, extending across the case, then led up onto the cylinder, which is grooved at 54 on each side of the rows of pins 16 to receive them, and then 125 carried horizontally forward to the flanges 24, forming the guides I, to which their other ends are secured.

The mechanism being in the position shown in Fig. 2, and assuming that the ends of the 130 strips 44 and 45 are just outside of the opening 52 and the end of the strip 46 underlies the rear end of the sight-opening 7, the operation of the register will be as follows: Now the

operator makes an entry on the upper strip 44 through the opening 9 in the case, which entry is transferred by the manifolding material to the other strips 45 and 46. He then 5 turns crank D forward, when pawl 13 on the pawl-carrier G engages with one of the teeth 12 on ratchet-disk F, thereby turning cylinder E until pin 15 on pawl-carrier G comes into contact with a stop-lug 55, (see 10 Fig. 3,) secured to the side 2 of the case, and stops the further revolution of the cylinder, this partial revolution of the cylinder being sufficient to feed forward only the desired 15 length of paper to form the slips when detached, the upper two strips passing forward over the top of the case and under the printing device, and the lower strip passing down the guides I inside the case as far as the cutting device, as seen in Fig. 3, leaving the 20 portion written upon directly under the sight-opening 7. The operator now turns shaft C backward; but as the cylinder is loose upon the shaft it remains at rest, (being prevented from any accidental backward 25 movement by a pawl 56, secured to the end of one of the cross-bars 10, engaging with the teeth 11 on the disk,) the pawl 13 riding freely over the teeth 12. When the mechanism is at rest, the cam c is close to arm 30 a of frame H, (see dotted lines in Fig. 2,) the pin 20 on said arms is against bracket h', and the finger 32 on shaft 31 is in contact with the shoulder on arm h². Now as shaft C is re- 35 volved backward the cam slides frame H forward, when the shoulder on arm h² rides over finger 32, rocking the shaft 31, and thereby depressing the pressure-arms K to the position shown in Fig. 3, so as to hold the paper taut while being severed. As frame H moves 40 forward, the movable blade J' of the paper-cutter is carried close under the stationary blade, severing the slip, (guides I being open at 57 to permit this operation of the cutting apparatus,) after which the end of arm h² 45 comes into contact with the extension 41 on link 40 and operates the printing device to make an impression on the upper strip in an obvious manner, when the upper two slips are severed from the strips by tearing against the 50 edge of the top portion 8 of the case. At this time the cam c is about to leave arm a, as seen in Fig. 1, and as it moves clear of the arm the frame H is drawn back to its normal position by spring 23, when finger 32 on shaft 31 rides over and in front of the shoulder on arm h², thereby permitting spring 33 to rock the shaft 31 backward and raise the pressure-arms K, releasing the slip to be filed. Pin 14 55 on pawl-carrier G now comes into contact with lever M, rocking shaft 35 forward, which causes the filing-arm L (in the second and subsequent operations when there is a paper slip in the guides) to carry the slip down over the file f when pin 14 moves clear of the lever, permitting the latter and the filing-arm to be thrown back into normal position by counter-weight m. The pin 15 on pawl-carrier G now

contacts with a lug 58 on the inner side of the case and arrests the further backward revolution of shaft C.

It will be apparent from the drawings that in the forward revolution of shaft C the frame H will remain inactive, as cam c will simply swing arm a in the arc of a circle until the former passes clear. Furthermore, the filing-arm will not be actuated in this movement of shaft C, because pin 14 on pawl-carrier G, coming into contact with the front edge of lever M, will cause the upper section of that lever to turn on its hinge, as seen in dotted lines in Fig. 3. It will be observed that each slip severed from strip 46 immediately precedes that portion of said strip on which the last entry has been made, which latter portion is left exposed to view through the sight-opening 7. The operator is thus enabled to make sure that he has made a correct entry and clear impression before the slip is severed and hidden from view.

When a number of slips have been accumulated on file f, the latter and its contents may be taken out of the case, the head 25 removed, a binder 59 (shown in Fig. 8) inserted in the hollow file, as represented in Fig. 9, and the file withdrawn, leaving the slips strung upon the binder, when the ends of the latter may be bent over in the ordinary manner, binding the slips together, as in Fig. 10. If desired, a tag 60 may be bound with the slips, as seen in Figs. 9 and 10.

Having thus described my invention, what I claim as new, and desire to secure by Letters Patent, is—

1. In an autographic register, a paper-cutter, a filing-compartment, mechanism for moving the paper into the compartment, and a movable arm for piling the paper within the compartment.

2. In an autographic register, a cutter for severing a strip of paper into slips, and a file for receiving the severed slips, in combination with a filing-arm for placing the slips upon the file.

3. In an autographic register, a paper-cutter, a filing-compartment, guides for directing the paper to the compartment, and an arm for removing the paper from the guides and piling it in the compartment.

4. In an autographic register, a filing-compartment containing a file for receiving slips of paper, and means for supporting a slip prior to filing, in combination with a filing-arm for placing the slip upon the file.

5. In an autographic register, a filing-compartment containing a file for receiving slips of paper, and means for supporting a slip prior to filing, in combination with an automatically-actuated filing-arm for placing the slip upon the file.

6. In an autographic register, a filing-compartment containing a file, a paper-carrying roll, feeding mechanism for moving the paper forward, a cutter for severing the paper into slips, and a slip-support within the filing-

compartment for supporting the paper previous to filing.

7. In an autographic register, a case provided with a filing-compartment having a file arranged therein, and a feed-roller located adjacent to the said compartment, in combination with guides extending within the filing-compartment and at an angle to the file, a paper-cutter for cutting a strip of paper into slips, and a filing-arm for forcing a severed slip onto the file.

8. In an autographic register in which a writing-tablet, a number of strips of paper, and interposed manifolding material are employed, mechanism for propelling the paper through the register, and a paper-cutter for cutting the under strip of paper into slips, in combination with mechanism intermediate the cutter, and the propelling operating mechanism, whereby the said paper is severed by the action of the propelling operating mechanism.

9. In an autographic register, a feed-roller, a paper-cutter, and a removable arm, to which the movable blade of the cutter is connected, in combination with a shaft and mechanisms carried thereby for actuating, respectively, the feed-roller and the movable arm.

10. In an autographic register in which a writing-tablet, a number of strips of paper, and interposed manifolding material are employed, feeding mechanism capable of being revolved in one direction only, while its propelling mechanism is revolute in either direction, and a paper-cutter for cutting the under strip of paper into slips, in combination with mechanism intermediate the paper-cutter and the propelling operating mechanism, whereby the paper is severed by the reverse movement of the latter.

11. In an autographic register, a feed-roller revolute in one direction only, a paper-cutter, and a movable frame to which one blade of the cutter is attached, in combination with a shaft revolute in either direction, and separate mechanisms carried by the shaft for engaging, respectively, with the feed-roller and with a movable arm attached to the frame, whereby when the shaft is turned in one direction the feed-roller will be revolved and when turned in the opposite direction the cutter will be actuated.

12. In an autographic register, a paper-carrying roll, mechanism for feeding the paper forward from said roll, and a case having an opening in its top for the exit of the upper strip or strips, in combination with a paper-cutter, guides for directing the under strip in the path of the cutter, a file for receiving slips severed from said strip, and a filing-arm to place the slips upon the file.

13. In an autographic register in which a writing-tablet, a plurality of strips of paper, and interposed manifolding material are employed, a case having an opening in its top for the exit of the upper strip or strips, and a

sight-opening forward of the exit-opening, in combination with mechanism for feeding the paper forward, a support for the under strip beneath the sight-opening, and an automatically-actuated paper-cutter for severing the under strip into slips, said cutter being located in the path of travel of said strip forward of the sight-opening, whereby the slip immediately preceding the last one written upon, which latter is visible through the sight-opening, is severed before the visible slip is moved from its position.

14. In an autographic register, a paper-carrying roll, means for feeding the paper forward from said roll, and a paper-cutter, in combination with guides for directing the paper in the path of the cutter, pressure-arms coacting with said guides for holding the paper while being severed, and a movable arm for removing the severed slip from the guides.

15. In an autographic register, a paper-carrying roll, means for feeding the paper forward from said roll, and a paper-cutter, in combination with guides for directing the paper in the path of the cutter, pressure-arms coacting with said guides for holding the paper while being severed, a file, and a movable arm for removing the severed slip from the guides and placing it upon the file.

16. In an autographic register, a paper-carrying roll, means for feeding the paper forward from said roll, and a paper-cutter, in combination with guides for directing the paper in the path of the cutter, automatically-actuated pressure-arms coacting with said guides for holding the paper while being severed, a file, and an automatically-actuated movable arm for removing the severed slip from the guides and placing it upon the file.

17. In an autographic register, a paper-carrying roll and a feed-roller, the latter being revolute in one direction only and provided with ratchet-teeth upon one end, in combination with a pawl-carrier revolute in either direction for engaging with the teeth to turn the roller, and stops for limiting the forward and backward revolutions of the carrier, whereby uniform lengths of paper are fed forward on the partial revolutions of the roller.

18. In an autographic register, a paper-carrying roll, mechanism for feeding the paper from the roll, and a paper-cutter for cutting the under strip of paper into slips, in combination with a movable arm, to which one blade of the cutter is pivoted, and a spring carried by the arm and bearing against the under side of the said blade for keeping the cutting-edges of the two blades in close contact while the paper is being severed.

19. In an autographic register, a paper-carrying roll, a main shaft revolute in either direction, and a feed-roller mounted upon said shaft and revolute with it only in a forward direction, in combination with a paper-cutter automatically actuated to sever the paper on a backward revolution of said shaft.

20. In an autographic register, a paper-carrying roll, a main shaft revoluble in either direction, and a feed-roller mounted on said shaft and revoluble with it only in a forward direction, in combination with a paper-cutter, a sliding arm to which one blade of the cutter is attached, a printing device operated by said arm, and a cam on the shaft for imparting a forward movement to the sliding arm 5 on a backward revolution of the shaft, whereby the paper-cutter and the printing device are automatically actuated.
21. In an autographic register, a paper-carrying roll and a feed-roller, the latter being revoluble in a forward direction only, in combination with a paper-cutter, a movable arm to which one blade of the cutter is attached, a shaft revoluble in either direction, a pawl-carrier on said shaft for turning the roller, 10 and a cam carried by the shaft for actuating the movable arm on a backward revolution of the shaft.
22. In an autographic register, a shaft and a pawl-carrier mounted thereon provided with a laterally-projecting pin, in combination with a rock-shaft carrying a filing-arm and a lever, the latter engaging the said pin, whereby when the said carrier is turned the rock-shaft will be rocked and thus operate the 15 filing-arm.
23. In an autographic register, a shaft and a pawl-carrier mounted thereon provided with a laterally-projecting pin, in combination with a rock-shaft carrying a filing-arm and a jointed lever, the latter engaging the said pin, and mechanism for returning the lever to its normal position after having been operated by the pin.
24. In an autographic register, a feed-roller 20 provided with ratchet-teeth at one end, a paper-cutter, and a sliding frame, to which one blade of the paper-cutter is attached, in combination with a shaft having one end provided with a cam for imparting a forward movement to the said frame, and a spring for

returning the frame to its normal position after having been actuated by the cam.

25. In an autographic register, a feed-roller provided with ratchet-teeth at one end, a paper-cutter, and guides for supporting a strip 50 of paper while being severed by the said cutter, in combination with a sliding frame, to which one blade of the paper-cutter is attached, a shaft carrying, respectively, a pawl-carrier for engaging with the ratchet-teeth, 55 and a cam for engaging with the sliding frame, a shaft carrying pressure-arms designed to coat with the guides to hold the paper strip taut while being severed, and fingers carried by the latter shaft, one of which 60 fingers engages with the sliding frame to bring the pressure-arms into engagement with the paper strip and the other connects with a spring for moving the pressure-arms out of engagement with the paper strip. 65

26. In an autographic register, a paper-cutter and a printing device, in combination with a sliding frame for actuating the paper-cutter and the printing device, and mechanism, substantially as described, for actuating the 70 sliding frame.

27. In an autographic register, a paper-cutter, a printing device, and a series of pressure-arms, in combination with a sliding frame which actuates the said mechanisms, and 75 means, substantially as described, for actuating the sliding frame.

28. In an autographic register, a printing device, arms connecting with the handle thereof, and pivoted links connecting with 80 the arms, one of which links is provided with an extension, in combination with a sliding frame which contacts with the said extension to depress the stamp and make an impression and mechanism for actuating the said frame. 85
